TABULATING MACHINE

Alvin E. Gray, Binghamton, N. Y., assignor to
 International Business Machines Corporation,
 New York, N. Y., a corporation of New York

Application October 2, 1931, Serial No. 566,443

4 Claims. (Cl. 235—92)

This invention relates to perforated card controlled machines and more particularly to a device for making electrical connections between various parts of the machine.

5 In the well known Hollerith tabulator, connections are made between various brushes adapted to sense the several columns in a perforated record card and the several orders of different accumulators so that any column on a card may be caused to control any order of any 10 accumulator. Also, when printing is being effected in such machines any order of an accumulator may be connected to any column of type so that the printing will be done in a desired position on the report sheet. Or if listing is being 15 done directly from the card any column on the card may be connected to control any column of type to cause printing to be done in the desired column on the report.

20 It is the usual practice to connect each brush to a plug socket on a plug board and connect each accumulator and each column of type to other plug sockets on the board. Connections are then made by plugging across these various 25 sockets as desired.

According to my invention, instead of plug sockets interconnected by loose plug wires, terminal contacts are provided to take the place of the sockets, and sliding members having bus bars 30 are provided to variously interconnect the terminal contacts instead of the wires formerly used to interconnect the plug sockets. The setting of the slides is controlled by a form report card. This card is different from the data cards which 35 are to be run through the machine and analyzed. The form card serves to control the setting of the several slides and determines the arrangement in which the various perforation sensing brushes are to be connected to the accumulator 40 and printing magnets so that data may be taken from any of the columns on the data cards and caused to control any of the orders of the accumulators or columns of printing elements by being variously connected to the magnets which 45 control the accumulating and printing. In other words, the present invention does away with the necessity of using plug wires to interconnect the sensing brushes and accumulating and printing magnets and provides a set of settable contact 50 slides to accomplish the same result. These slides may be set manually, if desired, or they may be set under control of the report card or, if desired, they may be set under control of the card and then particular ones may be reset man-

ually to differ from the set up effected by the card.

In other words, a card may have been punched to control the making of a particular form of report and in special instances it may be desired 5 to vary certain items in the report. These slight variations may be effected by first setting the various slides under control of the card and then changing the particular ones desired to effect the particular type of report required.

10 It is also common with these machines to bring about the taking of a total at the end of one group of cards and before accumulating commences under control of the next group. This totaling may be done automatically when the 15 machine detects a change from one group to the next. The feeding of cards at this time automatically ceases and the machine performs totaling operations, clearing the accumulators, if set to do so and then resuming accumulating or 20 accumulating and listing operations under control of the next group of cards. In some instances, the groups of cards are divided into major and minor groups as, for instance, when reports have been made covering the several 25 months and the various days of the months. In such cases, the groups of cards may be divided into minor groups covering the days and major groups covering the months. All the cards for 30 one day are placed together followed by the group of cards for the next day and so on to the end of the month. Also all of the cards for the several days of one month are placed ahead of cards for the succeeding month. At the end of a group of cards for a particular day the machine is automatically caused to print a total of 35 the data relating to that day's transactions and to then commence operation in connection with the data for the next day. At the end of the last day of the month, there is a change in the 40 major group as well as in the minor group and the total for the day is printed followed by the total for all of the days for that month. After this the machine commences analyzing cards for 45 the first day of the next month.

The setting of the machine to operate to take totals of major and minor groups is also effected by the setting of slides under control of the report or form card. At the end of each minor group total the accumulator may be caused to clear so 50 that each day's total will be separate from each other day or the machine may be set to take progressive or accumulative totals so that each day's total will be included with the totals of the preceding days of the month. The connections to 55

control this are also effected by the setting of the slides either manually or under control of the form report card. In other words, connections may be made with respect to each of the accumulators in the machine to cause them to clear after the printing of minor totals or after the printing of major totals. Also the accumulator which controls the printing of major totals will, of course, be set to accumulate data taken from all 10 of the cards of all of the minor groups included in the major group without any clearing operations until after the printing of the major total.

Also this accumulator may be set to accumulate progressive major totals so that when the last 15 major total is printed it will include all preceding major totals or, in other words, will constitute a grand total of all of the major totals.

Referring to the drawings:

Fig. 1 is a sectional side elevation of a device 20 constructed in accordance with my invention and adapted to be used to control the operation of the tabulating machine.

Fig. 1a is an enlarged detail of a control setting device.

Fig. 2 is a section of a different part of the device showing a different one of the movable slides.

Fig. 3 is a view similar to Fig. 2 with the parts in different positions.

Fig. 4 is a section taken on line 4—4 of Fig. 3.

Fig. 5 is a view of a punched card adapted to be used to control the setting of the several slides.

Fig. 6 is a sectional elevation of the device showing a slide adapted to control the connections for 35 effecting the zeroizing or clearing of the accumulators.

Fig. 7 is a section showing a slide used in connection with the major group control.

Figs. 8a, 8b, and 8c taken together constitute 40 a wiring diagram of a tabulating machine showing the control device arranged in accordance with my invention.

Fig. 9 is a modification of a punched form control-setting card.

In the drawings the complete tabulating machine is not disclosed as the details of the machine are very well known and are disclosed in numerous issued patents including Patent No. 1,762,145. Only so much of the machine is shown 50 diagrammatically as will be necessary to an understanding of the present invention and the manner in which it is used in connection with well known tabulating machines.

In Fig. 8a of the drawings, a stack of perforated 55 data cards 1 is shown in position ready to be fed one at a time by the card picker 2 to the feed rollers 3. Each card is fed downwardly between the upper sensing brushes 4 and cooperating contact blocks 5 and then between the lower sensing brushes 6 and corresponding contact blocks 7. As the successive index point positions of a column of one card are fed past the lower brushes 6, the corresponding index point positions of the next succeeding card are being fed past the upper 65 sensing brushes 4. The closing of electric circuits through the lower brushes 6 serves to control the machine to accumulate and print data contained on the card.

The upper brushes 4 by sensing a control designation ascertain whether a card being analyzed 70 belongs to the same group to which the card under the brushes 6 belongs. If the card under the brushes 4 belongs to the same group as the card under the lower brushes, it is permitted to pass 75 on to the lower brushes so that its data may be

taken and accumulated and printed. If the card under the upper brushes belongs to a different group, or in other words, if the card under the lower brushes is the last of a particular group the feeding of cards ceases momentarily while 5 the machine passes into a totaling cycle of operations during which the total of the previous group is printed. The accumulator in which the total was accumulated may then be cleared if desired after which the card feeding is resumed. 10 When this takes place the card which was under the upper brushes and brought about the taking of the total is fed to the lower brushes and its data is taken and accumulated and also printed, if the machine is set for such operations. 15

The machine is operated by an electric motor 8 driving a shaft 9 through a belt 10. A clutch 11 is adapted to connect a shaft 12 to the normally running shaft 9 in order to effect the driving of the cam shaft 13 and the feed rollers 3 20 and card picker 2. The motor 8 is shown within dotted lines in the upper part of the diagram along with its windings 14. The source of electric current for operating the machine is represented at 15 and may be connected to the lines 25 16, 17 by a switch 18. The operation of the machine may be started by depression of a start key 19. This will close contacts 20 and complete a circuit through the motor 8 as follows: from the positive side of the line 16 through the winding 30 of the motor 8, through relay coil 21 through the card feed clutch coils 22, relay coil 23, contacts 20 now closed, to the point 24, contacts 25a normally closed, stop button contacts 26 also normally closed to the point 27, contacts 28 which are closed at this time and to the negative side of the line 17.

The energization of the relay coil 23 closes contacts 23a so that the operator may now release the start key 19 and the circuit through 40 the motor and the card feed clutch relay 22 will continue through the contacts 23a, through the contacts 30 which are closed by the upper card lever 31 as soon as the first card fed reaches the position of this lever as indicated below the feed 45 rollers 3; from here, the current continues to the point 24, contacts 25a, contacts 26, point 27, contacts 28 to the other side of the line. As long as cards continue to pass through the machine they will keep the contacts 30 closed and 50 the machine will continue to operate. Should the cards fail to feed the contacts 30 will be permitted to open and this will break the circuit through the card feed clutch magnet 22 and the motor 8.

The machine may also be stopped at any time while cards are being fed, by the depression of the stop key 32. This also breaks the circuit through the motor and the card feed clutch. The stopping of the operation of the motor 8 60 and the deenergization of the card feed clutch magnet 22 may also be brought about by the opening of contact 25a. These contacts are normally closed but may be opened by the energization of relay coil 25 which is brought about by 65 a change in the group designation in the cards, or in other words, when the group control designation in the card under the upper brushes 4 differs from that in the card under the lower brushes 6. As disclosed in U. S. Patent #1,762,145, 70 to G. F. Daly and R. E. Page, relay coil 25 is controlled through a plurality of contacts 33. These contacts are adapted to be controlled by the comparison of the card under the lower brushes with the card under the upper brushes. 75

At certain times in the cycle of operation of the machine, the closing of a contact is adapted to feed current to these contacts 33 and if they are found to be closed the machine continues 5 to feed cards and accumulate data.

If, on the other hand, any one of these contacts has failed to close, the circuit will not be made at the proper time and the feeding of cards will stop and the machine will be caused 10 to take a total.

The circuit through the contacts 33 and the manner in which they are controlled will be brought out in greater detail in the description of the attachment or device which is subject 15 to the matter of the present invention.

The contacts 33 are connected to plug sockets 34. A plug socket 35 is also normally provided in the plug board of this machine so that a plug connection may be made from socket 35 20 to any of the sockets 34 and in this way eliminating from the circuit, all of the contacts 33 to the right of the socket 34 which is thus connected to socket 35. For instance, if group controlling is being effected through only one column on the card, it will only be necessary to use one of the contacts 33, namely, the one farthest to the left in Fig. 8a. In this instance, the socket 34 farthest to the left will be connected by plugging to the socket 35 and a circuit from line 36 will pass through the contact 33 to the first plug socket 34 across the plug line to the plug socket 35 and so forth. If, on the other hand, controlling is being effected through three columns of data on the cards, then 25 three of the contacts 33 will be employed and the plugging will be from the third socket 34 to the socket 35. In this instance, current from the line 36 will pass across the several contacts 33 if they are all closed to the third socket 34 30 and then to the socket 35, and so forth. If all of the ten contacts 33 are used for group controlling then the tenth socket 34 will be plugged to the socket 35 and it will be necessary for all ten of the contacts 33 to be closed in order 35 to effect continuation of the operation of the machine; failure of any one of the ten contacts 33 to be closed by similar data in the corresponding column of the cards will cause the circuit to remain open and the operation of the machine will change from accumulating to totaling.

The group control contacts 33 may be split by appropriate plugging so that some of them may be used to bring about the taking of sub-totals 55 when a change takes place in a minor group of cards and others may be used to bring about the taking of a grand total when a change takes place between major groups of cards. The manner in which the machine is controlled for the taking 60 of major and minor totals is more specifically disclosed in United States Patent #1,933,308 to James W. Bryce, dated October 31, 1933.

According to the present invention instead of plugging connecting wires between the sockets 34, 35, contact slides are moved to any of several possible positions to effect the desired connections between the sockets 34 and 35. In the carrying out of the present invention, the connecting slides and contacts may be applied to 70 the machine as an attachment and permanently connected to the plug sockets 34, 35; or the device may be built into the machine as an integral part thereof and connections to the contacts 33 may be made permanently, eliminating the sockets 34, 35.

In the lower part of the wiring diagram (Fig. 8a) additional plug sockets 37 are shown connected to the contact blocks 7 and other sockets 38 are connected to the contact blocks 5. The plug sockets 37, 38 are usually provided on the same plug board as are the sockets 34, 35. The sockets 37, 38 make it possible to connect the other parts of the machine to any of the brushes 4, 6, so that the data contained in various columns on the cards may be caused to control any 10 accumulator or any order in an accumulator and any column of type in the printing section of the machine. Sockets 39, 40 (Fig. 8c) also in the plug board are associated with the individual columns of the accumulators and type and the 15 connections from sockets 37, 38 to the sockets 39, 40 are made in various combinations as desired.

According to the present invention, these various connections are also effected through the 20 setting of contact slides. Here, again, the device may be connected to the accumulators by plug connections in sockets 39, 40, or the device may be built into the machine as stated and the 25 sockets and plug board omitted, the wires from the interconnecting slides to the accumulators and type control magnets being direct.

Other plugging sockets 41, 42 normally provided in the plug board for the purpose of connecting any of the brushes or columns on a 30 card to the group control device may also be omitted and the connections made directly to the control slides. For convenience, in the present instance, the control slides are shown as connected through the sockets 41, 42. 35

Referring now to Fig. 1, the casing or frame 43 is shown as having brackets 44 supporting a plurality of parallel bars 45 each of which is connected by means of a wire 46 to one of the upper brush contact blocks 7 of Fig. 8a. A 40 plurality of slides 47 mounted side by side are arranged below the bars 45 and extending transversely with respect thereto. Each bar 47 carries a plurality of contact brushes 48 adapted to engage the bars 45. The slides 47 are adapted to 45 be moved to the right or left to bring the brushes 48 into engagement with different bars 45. The brushes 48 are spaced along the slide 47 at a distance corresponding to the distance between ten of the bars 45. The lower edge of each 50 slide 47 is provided with similar brushes 48a, each pair of brushes 48, 48a being electrically interconnected through rivets 49 by which they are attached to the slide 47. The brushes 48a are adapted to slide upon contact strips 50 carried by an insulating block 51. 55

The length of the contact strips 50 is such that the slide 47 may be moved its full distance to the right or left without disengaging the brushes 48a from their respective strips 50. This limit 60 of movement of the slide 47 permits the engagement of brushes 48 over a range of ten of the bars 45. Thus, each group of ten bars 45 may be connected through its brush 48 and corresponding brush 48a to a contact strip 50 which is thus common to the ten bars 45. It will thus be seen that by adjustment of the slide 47 a particular contact strip 50 may be connected to any one of the corresponding group of ten sensing brushes 4 through the bars 45. In the lower portion of the casing a bracket 44a is shown supporting a plurality of bars 45a similar to the bars 45. Each bar 45a is connected by a wire 46a to one of the brush contact blocks 7 associated with the lower perforation sensing brushes 6. 75

Integral with the sliding bar 47 is another slide 47a. This slide carries contact brushes 52, 52a, interconnected by rivets 49a. The brushes 52 are adapted to cooperate with the bars 45a while the 5 brushes 52a are adapted to cooperate with contact strips 50a carried on an insulating block 51a.

The slide 47a is moved to the right or left with the slide 47 so that when the latter is adjusted to bring its brushes 48 into cooperation 10 with certain of the bars 45, the brushes 52 will be adjusted to cooperate with corresponding lower bars 45a. In other words, when a brush 48 is adjusted to cooperate with a particular one of the several upper perforation sensing brushes 4, a 15 brush 52 will be adjusted to cooperate with the corresponding lower perforation sensing brush 6. Between the upper and lower insulating blocks 51, 51a, are slides 53 provided with oppositely disposed contact brushes 54, 55, each separately 20 connected by a rivet 56 to the slide 53. The vertically aligned rivets 56 of a pair of opposite brushes 54 and 55 have their enlarged rear ends or bases seated in aligned recesses internally formed in the two layers which make up slide 25 53. As seated in these recesses, the aligned rivets have their bases spaced apart and out of engagement so that the opposite brushes 54 and 55 remain insulated from each other by slide 53, as indicated in Figs. 1 and 8b. The brushes 54 are 30 adapted to cooperate with contact strips 50 while the brushes 55 are adapted to cooperate with contact strips 50a.

The slide 53 is adjustable to the right or left to bring one of its sets of brushes 54, 55 into operation with corresponding upper and lower contact strips 50, 50a. There are five of the contact strips 50 and corresponding strips 50a and therefore five sets of brushes 54, 55. In any given position of the slide 53, one only of the 40 sets of brushes 54, 55 will cooperate with opposite strips 50, 50a. The slide 53 may be termed the tens order slide and the slide 47 the units order slide.

Assuming that the device is to be used in 45 connection with tabulating machines adapted to be controlled by perforated cards having 45 columns of data, there will be 45 of the bars 45 and 45a. The bar farthest to the right may be used in connection with card counting and the 50 bar farthest to the left may be a dummy to receive unused wires 46, 46a. There will also be five of the contact strips 50 and five strips 50a. The bars 45 will be grouped in four groups of ten each and a fifth group of five; the bars 55 45a being similarly grouped.

Assuming that the upper and lower card sensing brushes 4, 6 are numbered 1 to 45, the bars 45 and 45a may be similarly numbered beginning at the left from one to forty-five with an extra 60 bar at each end. If it is desired to connect a particular column of card sensing brushes to effect group control the slides 47, 47a and the slide 53 will be adjusted accordingly: for instance, assuming that control is to be effected 65 through column 26 on the card, corresponding brushes 4, 6, i. e. those reading that column, will be connected through bars 45, 45a and the slides, to connect with the group control mechanism, by moving slide 53 so that its brushes 54, 55 will 70 cooperate with the strips 50, 50a of the 20 order. The slide 53 is shown in such position in Fig. 1. The slides 47, 47a on the other hand, will be moved so that these brushes 48, 48a and 52, 52a 75 will cooperate with the bars 45, 45a corresponding to the card sensing brushes of the 6th, 16th,

26th and 36th columns. The slides 47, 47a in Fig. 1 are illustrated as adjusted to such position.

Thus it will be seen that the bar 45 of the 26th column is connected through brush 48, 48a to the 3rd contact strip 50 then through brushes 54, 55, 5 to the third one of the lower contact strips 50, then through brushes 52a, 52 to the bar 45a which is connected by its particular wire 46a to cooperate with the lower card sensing brush which cooperates with the 26th column on the data 10 card. It will be understood that there will be as many slides 47, 47a and intermediate slides 53 as there are possible control columns. In other words, it is common to provide possibility to 15 effect group control in connection with ten columns of perforations on the card. There may then be ten sets of the slides and contacts, etc. shown in Fig. 1. These slides may be adjusted so that they may be variously connected with the ten columns on the card. If some only of the 20 ten columns are to be employed for group control, the corresponding number of settings may be effected and the rest of the slides 47, 47a and 53 left in their normal or inoperative positions.

In Fig. 8b of the wiring diagram two sets of the contact slides disclosed in Fig. 1 are shown connected to control the operation of the tabulating machine represented by the wiring of Fig. 8a. Here two of the upper card sensing brush contact blocks 5 are connected through wires 46 to the bars 45 and several of the contact bars 7 associated with the lower sensing brushes 6 are connected through wires 46a to the lower bars 45a. The insulating blocks 51, 51a are provided with contact strips 57, 57a adapted to cooperate with brushes 58, 58a, brush 58 being electrically connected through a common strip 59 to all of the brushes 54, while brush 58a is electrically connected through a common strip 59a to all of the brushes 55. The strip 57 is connected by a wire 60 to one of the points or plug sockets 41 and the contact strip 51a is connected by a wire 60a to the opposite point or plug 42. Two of these sets of slides and contacts are thus shown connected to two sets of plugs 41, 42.

These plug points are interconnected by a magnet coil 61 in series with a pair of contacts 62. Each of the magnets 61 is associated with one of the sets of contacts 33 in Fig. 8a and is adapted when energized to close its set of contacts 33. It is understood that when any of these sets of contacts is closed during a card reading cycle of the machine, it will remain closed after the magnet 61 has become deenergized and is mechanically released later in the cycle after the controlling circuit has determined whether the machine shall continue to feed cards or take a total. It is also understood that the magnet 61 upon being energized opens the corresponding contacts 62 thus breaking the circuit through the magnet after the corresponding contacts 33 have been closed and locked in such position.

The manner in which the setting of the contacts 33 serves to control the operation of the machine to take totals after each group of cards has been analyzed is disclosed in the patent hereunto referred to. The manner in which these contacts are connected to take a total on a change in a minor group and also in a major group is fully disclosed in the aforementioned patent. It will be described sufficiently here, however, to show the manner in which it cooperates with the present invention.

It will be understood that after the machine has been started by the depression of the start 75

key and after the preliminary setting up of the machine has taken place, the major control relay contacts 63 and the minor control relay contacts 64 will both have dropped to open the upper contacts which are shown as closed in Fig. 8a and will close the lower contacts which are shown here as open. The opening of the upper contacts 63 and the closing of the lower ones are effected by the energization of the relay coil 63a, and the opening of the upper and closing of the lower contacts 64 are effected by the energization of relay coil 64a.

Assuming then, that these two coils are energized and are holding their lower contacts closed, current will pass from the line 16 through lower contacts 64, coil 64a, contacts C1, contacts L3, wire 65 to the other side of the line 17. After the cards have been analyzed to ascertain whether the group numbers on the upper and lower 20 cards are the same the cam C1 will permit the C1 contacts to open and if the group numbers on the two cards are the same, the current through the coil 64a will pass around the C1 contacts through the wire 36, the first contact 33, (assuming that we are group controlling on but one column) then through wire 66 to a bar 61, brush 68 carried by a slide 69 then to the common strip 70, brush 71, contact strip 72, wire 73, bar 74, brush 75, contact strip 76, brush 77, contact 78, wire 79 to the connection point 35, card lever contacts 80, which are closed at this time as long as cards are passing through the machine and back to the line 17.

By thus maintaining the coil 64a energized the lower contact 64 will remain closed and the machine will continue to feed and analyze cards and to accumulate and print the data taken therefrom. If the group control numbers on the two cards were different, the first group control 40 contact 33 would not have been closed as current would not have been fed simultaneously through the corresponding upper and lower brushes 4 and 6 and through the coil 61 (Fig. 8b) which serves to close the control contacts 33. Deenergization of coil 64a permits the contacts 64 to return to their normal position with the upper set closed. Current will then flow from line 16 through upper contacts 64 to relay coil 25, wire 65 to the other side of the line. The energization of coil 25 opens 50 the relay contacts 25a so that the current now flowing through the driving motor 8 and the card feed clutch 22 will fail and feeding of cards will stop.

Deenergization of the card feed clutch magnet 22 permits contacts 22a to close. Near the end of the card cycle, contacts L1 close momentarily. A switch 82 was, of course, closed before the machine was started if group controlling is to be employed. A circuit will now be set up from line 16, through the relay coil 83, reset motor RM, magnet 84, contacts 22a, contacts L1, stop key contacts 26 to point 27, contacts 28 and back to the line 17. The energization of magnet 84 closes contacts 84a so that after contacts L1 have opened, current will continue to flow through the reset magnet 84, contacts 84a, wire 85, contacts L2, to the other side of the line. This introduces a total or totals from the accumulator or accumulators which were used for accumulating the data taken from the group of cards which has now completed its passage through the machine.

Closure of contacts P1 shunts out relay magnet 84 so that the latter becomes deenergized permitting contacts 84a to open. A circuit through

the reset motor then continues through contacts P1, relay contacts 86, contacts L2 which are closed throughout a totaling or reset cycle back to the line 17. Near the end of the totaling cycle, contacts P1 open and the reset motor RM stops. 5 Also the contacts LP1 close near the end of the totaling cycle and a circuit is set up from the line 16 through contacts LP1, coil 64a, contacts C1, L3 and wire 65 to the other side of the line. The relay magnet 64a will now open the upper 10 set of contacts 64 and close the lower set. This will break the circuit through coil 25 permitting contacts 25a to close. The upper contacts 63 open before the beginning of the accumulating cycles and the lower contacts 63 close by energization of major control magnet 63a. When the machine is set for minor control alone, the parts 14, 15, 16, and 17 are set as shown in Fig. 8a, and as long as cards are feeding, when contacts L3 open, the major control magnet 63 is maintained energized by a major shunt circuit; the circuit being from the line 16 to lower contact 63, electromagnet 63a, wire 93, 94, 13, plate 14, brush 15, contact strip 16, brush 17, bar 18, wire 19, contacts 80, to the line 17. Current may 20 now pass through the operating motor 8 and card feed clutch 22 as follows: from the line 16, through motor 8, magnets 21, 22, 23, switch 88 which is closed, contacts P4 which close near the end of the totaling cycle, card lever contacts 89, 30 30, contacts 25a, 26 to point 27, contacts 28 back to the line 17. This causes resumption of card feeding and accumulating and listing operations.

Thus far, we have assumed that we were controlling the machine on but one column of the card. If controlling is to be effected from three columns on the card, it will be necessary to use three of the sets of contacts 33. The three columns of the card will be connected through the slides 57, 57a to control the corresponding three relay magnets 61. Also the minor control slide 69 will be moved to the right as viewed in Fig. 8a so that the brush 90 will engage the bar 67 designated 3. The brush 68 will now be out of engagement with all of its bars 67 but the brush 71 will continue in engagement with strip 72. Now when the contacts C1 are opened during the testing time, current will pass through lower contacts 64, relay magnet 64a, wire 36, the three sets of contacts 33 farthest to the left, then to the third bar 67, brush 90, strip 70, brush 71, contact strip 72, wire 73, bar 74, brush 75, strip 76, brush 77, strip 78 to point 35, contacts 80 back to the right side of the line. If any one of the three sets of contacts 33 fails to close by reason of a dissimilarity in the columns being used to control, the circuit through relay 64a will be broken. Upper contact 64 will then close and relay coil 25 will become energized opening contacts 25a to stop the card feeding and the operating motor 8, and the totaling and reset or totaling cycle will be started.

Assuming now that major and minor group control is to be employed, each using three columns to control, the slide 69 will be set so that the brush 90 will cooperate with the "3" bar 67 and the major selector bar 91 will be moved to the right so that the brush 92 will engage the "6" contact bar 67. The brush 75 will now be disengaged from the bar 74 but brush 77 will continue in contact with strip 78. The first, second, and third sets of contacts 33 are now connected for minor controlling and the fourth, fifth and sixth sets for major controlling.

The control relays 61 for these sets of contacts will be connected to the respective columns on 75

the card by the manipulation of the appropriate six sets of slides 47, 47a and 53. Now as long as the cards under the upper and lower brushes contain the same major and minor group numbers all of the contacts 33 in the control circuit will be closed so that current passing from the left side of the line for the minor control will pass through contacts 64, relay 64a, wire 36, then through the six sets of contacts 33 (including the major group) into the "6" bar 67, through brush 92, strip 76, brush 77, strip 78 to point 35, contacts 80 to the other side of the line 17. At the same time that this minor test circuit operates the major test circuit through its contacts 33 will be caused to operate by opening of cam contacts L3 which takes place at the same time that contacts C1 open. Current will then pass from the line 16, through lower contacts 63, holding relay 63a, wire 93, wire 94, contact strip 72, brush 71, contact strip 70, brush 90 (set to the "3" bar), then by way of such "3" bar 67 across the fourth, fifth and sixth sets of contacts 33, to the "6" bar 67, brush 92 (set to this point), contact strip 76, brush 77, strip 78 to point 35, contacts 80 to the line 17. Should a change in group number occur in the minor control column the minor control circuit will fail permitting lower contacts 64 to open and upper contacts 64 to close, but the major control test circuit will not be broken and the relay 63a will continue to hold the lower contacts 63 closed. The machine will then perform one totaling cycle of operations. On the other hand, if a change occurs in the major group control number the major control circuit as well as the minor control circuit will open and the lower contacts 63, 64 will both open and upper contacts 63, 64 will both be closed. This will cause the machine to perform two cycles of resetting and totaling operations.

Toward the end of the first of these cycles, contacts LP6 close for a short period and then re-open, but nothing happens at this time because contacts LP7 and lower contacts 64 are open. Immediately thereafter, contacts LP7 close completing the circuit through the relay coil 64a as previously described, causing the lower contacts 64 to be closed and the upper contact 64 to be opened. This does not deenergize relay coil 25 at this time because the upper contacts 63 are still closed. During the second resetting or totaling cycle, contacts LP6 will again close and a circuit will be closed from the line 16 to lower contact 64, contacts LP6, relay coil 63a, contacts L3, wire 65 back to the line 17. The energization of relay 63a will close the lower contacts 63 and open the upper ones. This breaks the circuit through relay coil 25 permitting contacts 25a to close. It may be pointed out here, that when relay coil 25 is energized coil 86a will also be energized to open the contacts 86. Thus, when lower contacts 64 are closed after the taking of major and minor totals the relay 86a continues to hold the contacts 86 open so that when, during that cycle, the contacts P1 are closed the current cannot pass through the contacts 86 and the relay 84 is permitted to remain energized. During the second resetting cycle, however, after the upper contacts 63 open to deenergize relay 25 the relay 86a will be deenergized at the same time and will close contacts 86 so that now when the contacts P1 close the circuit will be shunted from the relay motor around the relay 84, permitting the contacts 84a to open. Then, when the contacts P1 open, the circuit 75 will be completely broken through the reset-

ting motor RM. The closing of the contacts 25a will as has been pointed out now cause the operating motor 8 and card feeding clutch 22 to operate to resume card feeding and accumulating and listing operations.

The connecting of any of the columns on the card to the desired accumulators and orders thereof and also to the various columns of printing type is effected by the adjustment of slides 95, 96 (Fig. 8b). Each of the bars 45a as we have seen is connected to one of the lower sensing brush contact blocks 1. The adjustment of the sliding bar 96 will move the first of five lower brushes 97 into cooperation with any one of the first ten bars 45a. The second of these lower contact brushes 97 will be moved into cooperation with any one of the next ten bars 45a, etc. The five upper brushes 97a will continue to maintain contact with their respective contact strips 98. The movement of the tens sliding bar 95 on the other hand, determines which of its brushes 99 shall cooperate with one of the five contact strips 98. In Fig. 8b, the fourth of the several brushes 99 is shown as engaging the fourth contact strip 98. Thus, one of the columns ranging from 30—39 will be connected through the corresponding brushes 97a, 97 to one of the bars 45a. In the present instance, the units bar 96 is so adjusted that the several brushes 97 cooperate with the bars 45a of the 2nd, 12th, 22nd, 32nd, and 42nd columns so that the column 32 on the data card will be connected through the corresponding sensing brush to the accumulator order to which the slide 100 is connected. The circuit, tracing it from the right side of the line, will be through contacts 28 (Fig. 8a) to point 27, contacts 26, 25a, 30, 89, line 101 to the device designated 102 as a whole, wire 103, common bar 104, sensing brushes 6, corresponding contact bar 7, wire 46a, to the corresponding one of the bars 45a, brushes 97, 97a, contact strip 98, brush 99, common contact strip 105 to brush 106, contact strip 107, wire 108 to point 39 (Fig. 8c) through the accumulator magnet 109, contacts 110, back to the line 16.

The energization of relay 109 opens the contacts 110 and closes the contacts 111 in the well known manner. The energization of magnet 109 as is understood controls the particular order of the accumulator and is immediately deenergized by the opening of the contacts 110. The closing of contacts 111 on the other hand closes the listing circuit through 112. The mechanism associated with 112 for effecting printing when listing as well as when totaling is well known and need not be disclosed in detail here. If listing is not to be effected the contacts 113 serve to break the circuit through the listing magnet 112 but are closed during the resetting cycle or totaling.

In order to effect listing a switch is ordinarily provided to shunt the circuit across the contacts 113. According to the present invention the shunting of the circuit around the contacts 113 is effected through a slide 114 provided with contact brushes 115 electrically connected to each other. Movement of the slide 114 to the right so that two of the brushes 115 will engage the bars 116, 117 will close the circuit around the contacts 113. Thus, when contacts 111 are closed current will pass from the line 16 to the common bar 118, through contacts 111, magnet 112, common bar 119, wire 120, contacts 121, wire 122, bar 117, through brushes 115 to bar 116, wire 123, lower contacts P2 which are closed for printing, switch 124 back to the line 17. The bar 114 is also pro-

vided with a pair of brushes 125 which when the bar is moved one step to the right closes a circuit across the bars 126, 127. When the reset motor is energized the current passing through the coil 83 5 will close the contacts 83a so that current will pass from the line 16 through these contacts, through brushes 125 to bar 127 through the zeroizing magnet 129, relay contacts 130 held open by magnet 130a and which are closed when a 10 group change occurs, and back to the line 17. If resetting of the accumulators is to be effected the slide 114 is thus moved one step to the right. On the other hand, if it is not desired to reset the accumulators the slide 114 will be moved two 15 steps to the right and the brushes 125 will not bridge the gap between the bars 126, 127 but two of the brushes 131 will bridge bars 132, 133 so that current will be supplied to the printing magnet 112 as follows: from the line 16, through wire 20 134, bar 132, brushes 131, bar 133, wire 135, common bar 136, stepped contacts 137, printing relay 112, bar 119, contacts 121, contacts 113, which are closed during the resetting cycle, back to the other side of the line. The setting of the slide 25 114 two steps to the right to bridge the contact bars 132, 133 does not bridge the bars 116, 117 so that while current is supplied to the printing magnet during resetting cycles no current will be shunted around the contacts 113 during the 30 accumulating cycles and no listing will be effected. As the bars 126, 127 are not bridged by the brushes 125 the zeroizing magnet 129 will not be energized and the accumulators will retain the 35 values throughout successive total printing operations and thus produce progressive totals. If, progressive totals along with listing of the several items is to be effected the slide 114 will be moved three steps to the right, two of the brushes 131 will still bridge the bars 132, 133 and two of the brushes 115 will now bridge the bars 116, 117. The circuit through the printing magnets 112 will now be closed during successive card cycles 40 of the machine for listing and the circuit for printing will take place during resetting cycles across the bars 132, 133. For listing only the slide 45 114 will be moved four steps to the right so that the brushes 131 do not bridge the bars 132, 133 but two of the brushes 115 will bridge the bars 116, 117 to close the circuit through the printing magnet 112 during listing cycles.

Each of the slides 95 is connected to a link 145 reaching forward and provided with a depending pin 146 adapted to cooperate with a form card 55 147 carried by a movable frame 148. Each of the slides 96 on the other hand, passes around to the other side of the frame 148 and is provided with a link 149 having a depending pin 150 also cooperating with the form card. As shown in Fig. 1a the form card 147 is mounted directly over a perforated plate 151 integral with the carriage 148. The form card is adapted to be perforated so that the pins 146, 150 may reach through the card and into any of the perforations in the plate so that as the frame 148 is moved to the right, it will move the slides 95, 96. The frame 148 is provided with studs 152, 153 cooperating with slots 154 in plates 155 which in turn are provided with studs 156 adapted to slide laterally in slots 157 60 in the frame 43.

Cams 158 mounted on a shaft 159 carried by the plates 155 cooperate with the studs 152, 153 so that as the shaft is rotated, the cams will serve to raise or lower the frame 148. In this way, the 70 form card 147 may be moved upwardly to coop-

erate with the pins 146, 150 and may be lowered to disengage the pins. Also fixed to the shaft 159 is an arm 160 provided with a stud 161 cooperating with a slot 162 in the side of frame 43. A crank 163 is provided for rotating the shaft 159.

The normal position of the parts is shown in Fig. 3, the form frame 148 being at the left side of the machine and in raised position. Turning of the crank 163 clockwise to the position of Fig. 2 will, through the stud 161 cooperating with slot 162, cause the plate 155 and frame 148 to be moved to the right as shown in Fig. 2. Further rotation of the crank 163 from the position of Fig. 2 to that of Fig. 1 causes the lowering of the frame 148 by the cam 158. The form card is 15 shown in Fig. 5. The card is divided into five fields designated 1 to 5 with perforations for controlling accumulating in the five sets of accumulators. These fields are divided into upper and lower portions 164, 165. Each upper field is provided with eight perforation positions in horizontal rows there being four such rows. In other words, there are eight columns of perforation positions with four positions to each column. The lower portion of the field 65 on the other 20 hand is provided with eight columns with nine perforation positions to a column. Each of the upper columns of perforation positions corresponds with one of the slides 95 and each of the lower columns corresponds with one of the slides 30 96. When the form card is in position the link 145 cooperates with its corresponding column of perforation positions in the upper portion 164 of the field and the link 149 cooperates with its column in the lower portion of the field 165. 35

The particular column having been punched in its upper and lower portions will now permit the pins 146, 150 to drop through the perforations as the frame 148 is moved to the right. The positions of the perforations will determine how far the slides 95, 96 will be moved by the movement of the frame its full distance to the right. By punching all of the columns as desired, the movement of the frame 148 to the right will thus set all of the slides 95, 96 and in this way effect 40 the desired connections between all of the columns on the card and all of the columns in the accumulators and the printing type. Each of the links 145, 149 is shown as having upward extensions 145a, 149a so that after all of the slides 50 have been set under control of the form card individual changes may be made by manually moving the links 145, 149 to any desired position. A setting of the slides 47, 47a (Figs. 1 and 85) is effected through a link 149b and the setting of the slides 53 is effected through a link 145b. These links cooperate with the ten columns in the upper and lower portions 166, 167 55 near the left end of the form card 147 (Fig. 5), the slide 53 being controlled by the upper columns of perforations in the portion 166 of the field and the slide 47, 47a being controlled by the lower perforations in the portion 167. Column ten would be selected by a "10" perforation in field 166 and no perforation in field 167 60 as the contacts 52 are normally on the "10" bar. Selection of field 20 would in like manner be effected by a perforation in the "20" position in the field 166, etc. The slides 114 (Fig. 8c) are shown in detail in Fig. 6. These slides are provided 65 with links 114a having pins 114b adapted to cooperate with the perforations in the field 168. There are five columns of these perforations with four perforation positions to a column. Each column will be punched in accordance with the 75

nature of the control desired in connection with the five counters or sets of accumulators and will cause the respective slides 114 to be moved from the normal position of Fig. 8c to any one 5 of the four positions described.

In Fig. 6 the slide 114 is shown as having a brush 169 sliding over the bars 45a. This brush is not electrically connected to anything and serves only as a guide for the slide 114. Details 10 of the slides 69, 91 are shown in Fig. 7. The two slides are mounted side by side and so only one of them shows in this view. The slide 91 is provided with a link 91a adapted to cooperate with the column 170 which is farthest to the left on 15 the form card of Fig. 5. The slide 69 on the other hand is connected by a link 69a to an offset pin 69b adapted to cooperate with the lower portion 170a of the same column of perforations on the form card.

20 While the machine is in operation, the crank 163 may be left in the position of Fig. 2 or that of Fig. 1. After having used the machine under control of the form card the parts may be restored to their normal positions by turning the 25 crank 163 clockwise to the position of Fig. 3. This not only restores the frame 148 to starting position but also through a restoring bar 171 carried by the carriage or frame 148 restores all of the slides to their normal positions. For this 30 purpose, the links 145 and slides 96 are provided with projections 172, 173 reaching into the path of the restoring bar 171. The bar thus engages these projections as the frame 148 is moved to the left and carries the slides along in this direction. In Fig. 1 the slides 47, 47a are restored 35 by cooperation of the bar 171 with the connecting portion 174. The form cards 147 of Fig. 5 are provided with printed indications of the positions for punching and the punching is done 40 according to the nature of the report to be made out on the machine under control of the perforated record cards. In this connection the operator wishing to connect the 33rd column of the 45 2nd accumulator in the machine will punch 33 in the 26th or units column of the second accumulator on the form card. In other words, as shown in Fig. 5, the 26th column on the form card is punched in the tens field on the line designated 50 39 and in the units field on the line designated 3.

In Fig. 9, a modified form card 147a is shown. This card may be made up of a very thick lower portion covered by a thin upper portion 147b, the lower portion may be provided with perforations 55 147c in all of perforation positions and the upper portion will normally have no perforations. When it is desired to prepare the card to control the

making of a particular kind of report the operator will use a pencil to puncture the covering 147b directly over the several holes 147c.

I claim:

1. In a punched card accounting machine; 5 electric brushes for sensing perforations in record cards; electric contacts, one for each brush and connected thereto; a plurality of multi-order accumulators; an actuation control element for each order; a set of electric contacts, for each element; and slides having contact interconnecting means, each of said slides being movable into variable cooperative relation with said first-named contacts and the contacts of one said set to selectively connect any one of said brushes 10 with the accumulator order associated with the latter set of contacts.

2. In a punched card accounting machine; 20 electric brushes for sensing perforations in record cards; a set of electric contacts, one connected to each brush; a plurality of multi-order accumulators; an actuation control element for each order; a set of electric contacts connected to each element; slides having contact interconnecting means, said slides being movable into 25 variable cooperative relation with the contacts of said sets to selectively connect any brush with any accumulator order; and a controlling form card cooperating with the slides for controlling the setting thereof.

3. In a punched card accounting machine having accumulators; two sets of electric brushes for sensing perforations in two record cards simultaneously; terminal contacts connected to said brushes; total taking control means; and slides having contact interconnecting means connected with the total taking control means, said slides being movable across said contacts to selectively connect corresponding contacts of the two sets to the total taking control means 40 for causing the machine to take totals under control of the record cards.

4. In a punched card accounting machine having accumulators; two sets of electric brushes for sensing perforations in two record cards simultaneously; terminal contacts connected to said brushes; total taking control means; slides having contact inter-connecting means connected with the total taking control means, said slides being movable across said contacts to selectively connect corresponding contacts of the two sets to the total taking control means for causing the machine to take totals under control of the record cards, and a punched form card cooperating with the slides for controlling 55 the setting of the slides.

ALVIN E. GRAY.
